UNITED STATES PATENT OFFICE

134,742

DESIGN FOR A MOTORCYCLE ENGINE SIMULATING ATTACHMENT FOR BICYCLES

Charles W. Redlund, West Hartford, Conn.

Application May 26, 1942, Serial No. 107,013

Term of patent 7 years

To all whom it may concern:

Be it known that I, Charles W. Redlund, a citizen of the United States, residing at West Hartford, in the county of Hartford and State of Connecticut, have invented a new, original, and ornamental Design for a Motorcycle Engine Simulating Attachment for Bicycles, of which the following is a specification, reference being had to the accompanying drawing, forming a part thereof.

In the drawing:

Figure 1 is a side elevation of a motorcycle engine simulating attachment for bicycles showing my new design.

Fig. 2 is an edge view thereof.

I claim:

The ornamental design for a motorcycle engine simulating attachment for bicycles, as shown.

CHARLES W. REDLUND.
